(57) **CLAIM**

The ornamental design for a board-free roof jack clip, as shown and described.

DESCRIPTION

FIG. 1 is a left front perspective view of a board-free roof jack clip showing our new design;

FIG. 2 is a front elevation view thereof;

FIG. 3 is a rear elevation view thereof;

FIG. 4 is a top plan view thereof;

FIG. 5 is a bottom plan view thereof; and,

FIG. 6 is a left side elevation view thereof; the right side elevation view being a mirror image of FIG. 6.
